UNITED STATES PATENT OFFICE.

WALTER S. BRIDGES, OF CHICAGO, ILLINOIS.

CUSPIDOR.

1,119,679.

Specification of Letters Patent.

Patented Dec. 1, 1914.

Application filed May 13, 1914. Serial No. 838,297.

To all whom it may concern:

Be it known that I, WALTER S. BRIDGES, a citizen of the United States, residing at Chicago, in the county of Cook and State of Illinois, have invented certain new and useful Improvements in Cuspidors, of which the following is a specification.

This invention relates to improvements in 10 cuspidors, and its object is to provide a novel and improved structure which will prevent the contents of the cuspidor from being spilled if it should be accidentally upset.

The invention also has for its object to 15 provide a cuspidor which is reversible and which can be easily emptied and cleaned.

These objects are attained by means of a combination and arrangement of parts to be hereinafter described and claimed, reference 20 being had to the accompanying drawing, in which—

Figure 1 is an elevation of the cuspidor, and Fig. 2 is a central vertical section thereof.

Referring specifically to the drawing the 25 body of the cuspidor comprises two sections 5 and 6, respectively, of any suitable material and form, although preferably of cylindrical shape. These two sections are screwed 30 together, as indicated at 7. Any other means may be provided for separably connecting the sections. The top of the section 5 has an entrance in the shape of an inwardly extending funnel 8, and a similar funnel 9 extends 35 inward from the bottom of the section 6. The two sections and their funnels are counterparts, and the cuspidor may, therefore be positioned with either section uppermost. The inner ends of the funnels are opposite

each other and spaced apart a sufficient distance to accommodate a ball valve 10, the same normally seating on the mouth of the bottom funnel, which latter is shaped to form a seat for the valve. The mouth of the top funnel is also shaped to form a seat 45 for the valve when the cuspidor is reversed. The valve therefore always forms a closure for the lower funnel. The space between the mouths of the funnels is such that the valve cannot slip out of said space into the body 50 of the cuspidor.

It will be evident from the foregoing that the contents of the cuspidor cannot spill if the same is upset, and the cuspidor may be righted on either end, the ball valve automatically seating over the mouth of the lower funnel. To empty or clean the cuspidor it is necessary only to separate the sections 5 and 6.

I claim:

1. A cuspidor comprising a body having an entrance at each end, with valve seats at 60 said entrances, inside the body, and a ball valve in the body normally engaging the entrance at the bottom for closing the same. 65

2. A cuspidor comprising a body having funnels extending inward thereinto from each end, the inner ends of the funnels being spaced apart and having valve seats, and a ball valve in the space between the inner 70 ends of the funnels and normally engaging the seat of the lower funnel.

In testimony whereof I affix my signature in presence of two witnesses.

WALTER S. BRIDGES.
